UNITED STATES PATENT OFFICE.

EBERHARD KOCH, OF GROSSE TETE, LOUISIANA.

TURPENTINE AND RESIN EXTRACTOR.

1,127,452.

Specification of Letters Patent. Patented Feb. 9, 1915.

Application filed November 29, 1912, Serial No. 734,117. Renewed July 1, 1914. Serial No. 848,480.

To all whom it may concern:

Be it known that I, EBERHARD KOCH, a citizen of the United States, residing at Grosse Tete, in the parish of Iberville and State of Louisiana, have invented new and useful Improvements in Turpentine and Resin Extractors, of which the following is a specification.

This invention relates to an apparatus for extracting turpentine, rosin and other volatile substances from wood, the primary object of the invention being to provide an extractor wherein the volatile constituents may be separated by the action of steam, while the mass of wood is being agitated, thus facilitating the separation of the volatile products and enabling the same to be obtained in a highly pure condition.

A further object of the invention is to provide an extractor of the character described, wherein provision is made for the introduction of a solvent for facilitating the separation of the finer quantities of volatile constituents and recovery of the rosin, enabling substantially all of the volatile constituents of the wood to be driven off and obtained.

The invention consists of the features of construction, combination and arrangement of parts hereinafter fully described and claimed, reference being had to the accompanying drawings, in which:—

Figure 1 is a vertical section through an extractor embodying my invention. Fig. 2 is a horizontal section of the same.

Referring to the drawing, 1 designates the extractor, comprising a vertical cylinder or casing closed at its upper end by a head or removable jacket 2 and having a surrounding jacket 3, forming a dead air space to prevent radiation of heat from the extractor. If desired, the space between the extractor cylinder and jacket may be filled with any suitable heat insulating material.

The extractor 1 is provided with a conical or tapered bottom 4 communicating through a connection 5 with a centrifugal separator 6. In the connection 5 is a valve 7, which controls communication between the extractor and separator. Through this outlet connection the rosin and oleoresin may be discharged for treatment in the separator 6, allowing resin of a high degree of purity to be obtained. The conical bottom 4 is detachably secured in position in an airtight manner, and may be removed at

the completion of each extracting action for the discharge of the refuse wood.

Arranged within the bottom of the body of the extractor is a spider 8 provided with a bearing 9 for the lower end of a shaft 10 carrying a series of radial agitator blades 12. The lower end of the shaft is stepped into the bearings 9, so that it may be readily applied and removed, and the upper end of the shaft is journaled in and extended outwardly through the cover 2 and provided with a coupling 13 for connection with any suitable type of driving element, whereby the agitator may be rotated from any suitable source of power. The blades 12 of the agitator operate to constantly stir up and agitate the mass of wood under treatment in the extractor, to facilitate circulation of the extracting agents and the separation and discharge of the volatile constituents of the wood.

Arranged within the extractor is a manifold 14 communicating with a valved inlet 15 and provided with inwardly extending perforate nozzles 16 which are arranged on lines between the agitator blades 12, and thus coöperate therewith to effect thorough agitation of the wood when the agitator is in action. These nozzles are designed to inject steam into the mass of wood at various points, to drive off the volatile constituents without raising the temperature of the vapors to such a degree as to separate them into other component gases or render them incapable of being condensed. The top or cover 2 is provided with an outlet 17 communicating with a valved standard pipe 18, from which a valve conducting pipe 19 leads to any suitable type of condenser in which the turpentine and other vapors are condensed for subsequent recovery. A valved inlet 21 is provided at the lower end of the extractor for the introduction of a hydrocarbon or other suitable liquid solvent.

In operation, the cover 2 is removed and the wood in a finely comminuted condition introduced into the extractor, after which the cover is applied in position, the agitator set into operation and the valve in the steam inlet 15 opened for the supply of steam through the nozzles of the manifold. The temperature of the mass of wood is raised by the injected steam, causing the volatile constituents thereof to be liberated, the resin and other heavier constituents feeding downward by gravity into the

tapered bottom 4, while the turpentine and other lighter volatile constituents discharge through the pipe 19 to the condenser. The agitator in this operation not only facilitates the circulation of the steam through the mass of wood, and the liberation and discharge of the resin and lighter volatile constituents, but permits also of the escape of the water of condensation which flows 10 downward with the turpentine, thus keeping the mass of wood heated to the required temperature and preventing the accumulation of any condensed moisture therein. After the greater portion of the 15 turpentine and resin have been driven off the motion of the agitator is arrested, the steam supply cut off, and a solvent introduced through the pipe 21, which solvent passes up into the mass of wood and extracts the remainder of the volatile constituents. As soon as the proper amount of 20 solvent is introduced, the valve in the pipe 21 is closed and the steam inlet valve opened, whereby a further supply of steam is injected through the nozzles to flash the solvent into vapor, so that it will pass off with the lighter volatile constituents to the condenser for separation and recovery. When 25 all the available constituents have been extracted the steam supply is cut off, the motion of the agitator arrested, and the valve 7 opened for the discharge of the resin and oleoresin into the separator 6, which is then operated in any preferred manner to secure 30 the delivery of a highly pure resin. The bottom 4 is then detached and the refuse wood discharged, after which the extractor 35 may be filled with a fresh charge of wood for a repetition of the operation above described.

The advantages arising from my improved construction are, that the constituents of the wood are liberated and obtained without heating them to an objectionable degree, 40 thus enabling a larger quantity and a better quality of the turpentine and other products

to be obtained; the agitation of the wood during the injection of the steam throughout the mass of the wood insures the thorough heating of the wood and liberation of the 50 volatile constituents in a rapid manner; and by the introduction of a solvent together with steam during the final stage of operation any remaining quantity of the volatile constituents which cannot be driven off by the 55 use of heat alone will be liberated. Furthermore, the construction described permits of the ready separation of the resin from all impurities, and the obtention of the turpentine and other volatile vapors in a condition free from all foreign odors and other contaminating substances.

I claim:

An extractor of the character described comprising a vessel having a heat insulating jacket and provided at its upper end with a vapor collection space having a valved outlet and at its lower end with a conical resin collection space provided with a valved outlet, a spider disposed within the vessel 70 above said conical lower end, said spider being provided with a bearing, a shaft stepped in said bearing and extending vertically within the vessel and outwardly at the top thereof, laterally projecting agitator 75 blades upon said shaft at different elevations, a manifold disposed within the vessel, comprising upper and lower rings and vertical pipes, opposite series of steam injection nozzles projecting from said pipes and alternating in arrangement with the agitator blades, a steam supply conductor connected with the upper ring of the manifold, and a conductor for the admission of a volatile solvent communicating with the lower end 80 of the extractor.

In testimony whereof I affix my signature in presence of two witnesses.

EBERHARD KOCH.
